CLAIM

The ornamental design for a baseball sliding mitt as shown and described.

DESCRIPTION

FIG. 1 is a front view of a baseball sliding mitt showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof; and,

FIG. 7 is a perspective view of the baseball sliding mitt.

The perforated pattern shown on the claimed design forms no part of the claim thereof. The broken lines in the drawings depict environmental structure and boundaries and form no part of the claimed design. The contrast in shading type between straight shading and stipple shading represents a contrast in appearance as shown.
